Primary Examiner — Darlington Ly(74) *Attorney, Agent, or Firm* — Klintworth & Rozenblat IP LLP**CLAIM**

The ornamental design for a tile lippage threaded post, as shown and described.

DESCRIPTION

FIG. 1 is a bottom perspective view of a tile lippage threaded post incorporating my new design;

FIG. 2 is a top perspective view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines in the drawings illustrate portions of the tile lippage threaded post that form no part of the claimed design.
